UNITED STATES PATENT OFFICE.

LEVI H. MONTROSS, OF CAMDEN, NEW JERSEY, ASSIGNOR TO THE MONTROSS MANUFACTURING COMPANY, OF SAME PLACE.

MANUFACTURE OF SHINGLE SIDING AND MACHINERY THEREFOR.

SPECIFICATION forming part of Letters Patent No. 529,661, dated November 20, 1894.

Application filed November 2, 1892. Serial No. 450,747. (No model.)

To all whom it may concern:

Be it known that I, LEVI H. MONTROSS, a subject of the Queen of Great Britain and Ireland, and a resident of Camden, New Jersey, have invented certain Improvements in the Manufacture of Shingle Siding and Machinery Therefor, of which the following is a specification.

The object of my invention is to provide a method and means whereby siding strips or clap boards such as are ordinarily used for building purposes may have representations of shingles formed in relief thereon, as set forth, for instance, in my application for patent filed August 25, 1891, Serial No. 403,672. This object I attain in the manner hereinafter set forth, reference being had to the accompanying drawings, in which—

Figure 1, is a side view of a machine constructed for the manufacture of shingle-siding strips in accordance with my invention. Fig. 2, is a view of the opposite side of the machine, with the driving pulleys removed. Fig. 3, is a plan view of the machine. Figs. 4 to 9, inclusive are detached views of parts of the machine; and Figs. 10, 11 and 12, are diagrams illustrating a certain feature in the operation of the machine.

In carrying out my invention the representation of the shingles in relief upon the face of the strip is effected by the action of a pair of cutting knives and a circular saw, the latter being reciprocated across the face of the strip and the knives being shaped to accord with the desired contour of the recesses to be formed in the face of the strip, one of these knives working at right angles to said face so as to form incisions in the strip, and the other knife working in a direction parallel to the face of the strip, but some distance back of said face so as to cut out a chip from the space bounded by the incisions formed by the other knife, the knives operating, by preference, in the manner hereinafter set forth so as to follow each other in their action, and form chips of different thickness by successive cuts.

In the drawings A represents the fixed frame of the machine to suitable bearings a on which is adapted the driving shaft A' which has fast and loose pulleys a' a'' and carries a pair of

eccentrics B and D, a spur pinion F, and a belt wheel or pulley G.

The strap of the eccentric B is connected by an adjustable right and left threaded rod 55 b to a slide B' which is free to move back and forth in suitable guides b' at the top of the fixed frame, said slide B' carrying a cutter B² of the shape desired for the recess to be formed in the face of the strip, the knife in 60 the present instance being in the form of an inverted V, as shown in Fig. 4. The cutter B² is mounted upon a supplementary slide B³ which is adjustable laterally across the face of the slide B' so that the lateral position of 65 the knife B² can be varied as desired.

The strap of the eccentric D is connected by a rod d to a lever D' hung to a depending frame d' and connected by a rod d² to a slide D² which is guided in suitable vertical ways 70 d³ on the fixed frame and has a transverse guide d⁴ to which is adapted a second slide D³ carrying the vertical cutter D⁴ which is shaped to conform with the cutter B², as shown in Fig. 5. The spur wheel F meshes with a 75 like wheel F' carried by a shaft H which is mounted in suitable bearings f on the frame of the machine, and carries a pair of cams h, a crank disk i, and a combined cam and crank disk m. The cams h act as shown in Fig. 6 80 upon sliding boxes h' which are connected by rods h² to a work carrying head J at the outer end of the machine, the lower rod h² being supported upon suitable shoulders on the fixed frame as shown in Fig. 5, so as to provide for the vertical support of said head, and yet permit the desired inward and outward movement of the same.

In suitable guides on the head J is mounted a slide bar K (Fig. 7) which has at each end 90 projecting plates k with bearing lugs or fingers k' rounded upon their outer faces, each plate k also having a spring plate or finger k² so that when a siding strip is mounted upon the plates K its inner face, that is to say, the 95 face toward the knife B² will bear against the rounded faces of the lugs k' and its outer face will be acted upon by the spring plates or fingers k². The strip also passes between rollers n and the vertical portion of the head 100 J, and mounted on a lug n' on the said head is a lever n², the long arm of which is acted

upon by the spring n^3 while its short arm is toothed or roughened and serves to press downward upon the strip and thereby retain the same in proper vertical position upon the head and also to prevent any backward movement of the strip. (See Fig. 8.) If transverse reciprocating motion is imparted to the slide bar K, the strip held between the lugs k' and spring fingers k^2 will, on the forward movement of the slide bar, be carried along with the same, the lever n^2 yielding to permit such movement, but on the backward movement of the slide bar K the lever n^2 will grip and hold the strip, and the lugs k' and fingers k^2 will slide on the same until the direction of movement of the bar K is again reversed, so that intermittent forward feeding movement of the strip is thus effected, and the knives B^2 and D^4 are caused to act upon different parts 20 of the strip in succession. Reciprocating movement is imparted to the slide bar K from the crank disk i on the shaft H by means of devices best shown in Fig. 2. The pin of said crank disk i is connected by a rod i' to an arm i^2 on a rock shaft i^3 which carries a bevel wheel i^4 , the latter meshing with the bevel pinion i^5 on a shaft i^6 which carries a crank i^7 having a pin which is connected by a rod i^8 to the slide bar.

30 While I prefer the mechanism described for effecting the feeding of the strip, it will be evident that other known forms of feeding devices could be used without departing from the main features of my invention.

35 As shown in Figs. 1 and 3, the belt pulley G has a belt g which drives a pulley g' on a shaft g^2 carried by the lower ends of a lever M and arm M' both hung to the shaft A' and connected by a transverse bar M² so as to form a 40 swinging frame which will be referred to hereinafter. The shaft g^2 has a belt pulley g^3 to which is adapted a belt g^4 also adapted to a pulley g^5 on the spindle x' of a circular saw x, said spindle being adapted to bearings in 45 the upper ends of arms N, N' movably hung at their lower ends to the shaft g^2 .

50 The rear arm of the lever M is connected by a rod m' to a crank pin m^2 on the disk m , so that as said disk rotates a rising and falling movement will be imparted to the saw, and the latter will be carried vertically across the face of the strip so as to form a kerf therein. In order to regulate the character and depth of this kerf I employ a guide bar P 55 suitably mounted upon the carrying head J, and serving, by contact with one of the bearings of the saw spindle or with a collar on said spindle to limit the approach of the saw toward the strip, so that by varying the shape 60 or angle of this guide bar the kerfs may be made of varying depths.

65 The saw is pressed toward the strip by the action of a spring leg s at the upper end of an arm S pivoted to the shaft g^2 , this spring leg acting upon the bearing at the upper end of the arm N which carries the saw spindle, a constant backward pull being exerted upon

the arms N N' by a spring N² which acts upon a bar N³ connecting said arms and is fastened at its rear end to a pin N⁴ projecting from 70 the lever M. Forward movement is imparted to the upper end of the arm S and its spring leg s at the proper time by means of the cam disk m , said disk acting upon a lever m^3 which is connected by a rod m^4 to one arm of 75 a lever m^5 hung to a suitable stud on the fixed frame, the other arm of said lever having a pin m^6 bearing upon the lever S. By this means the saw, during one of its reciprocating movements, say during the upward movement, 80 may be caused to act upon the strip and to cut a kerf therein of a character and depth depending upon the guide bar P, the saw being then withdrawn from action upon the strip and held out of action during the reverse or downward movement.

85 The object of imparting the in and out movement to the work carrying head and its feeding devices is to provide for forming the recesses in the face of the strip by cutting 90 from said strip successive chips of different thicknesses. For instance, the first cut of the knives may be effected while the table is in its outward position so as to cut from the strip a thick chip y as shown in Figs. 10 and 95 11, for instance, and the table may then be moved inward slightly so that on the next action of the knives a thin chip y' is removed from the base of the recess previously formed, as shown in Fig. 12. I find that by this 100 means a clean-cut and sharply defined recess is formed so that the representations of the shingles will have the desired clean and sharp outlines. It is preferable to give the horizontally acting or incising knife B^2 a slight lead 105 over the vertically acting or chip cutting knife D^4 , so that the knife B^2 will have made its incision, as shown in Fig. 10, before the knife D^4 reaches the limit of its upward stroke, and said knife B^2 will have been withdrawn slightly by the time the knife D^4 is 110 fully elevated so that the latter may cross the incisions, as shown in Fig. 11, and thus insure the cutting loose of the chip.

115 I find it advisable to provide the block B^3 which carries the knife B^2 with projecting pressers t located adjacent to the knife blade, and projecting slightly beyond the same so that they will strike the face of the strip and be compressed thereby on the forward movement of the knife and hence by their re-action will press the strip away from the knife on the rearward movement of the latter, and in order to insure the withdrawal 120 of the chips y, y' from the recesses formed 125 by the knives, I combine with the knife D^4 a spring presser v (Fig. 9) for engaging with the chip and confining the same against the knife so that the latter will pull the chip clear from the recess on its downward movement.

130 It will be observed that the outward strain upon the work carrying head caused by the thrust of the knife B^2 against the strip is transmitted through the rods h^2 to the boxes

h' and thence to the shaft *H* so that the strain upon the main frame *A* is a compression strain between the bearings of the shafts *A'* and *H*, there being no tensile or stretching strain 5 upon any portion of the main frame, such strains being exerted wholly upon and resisted by the rods *h*². The use of the rods *h*² in the manner described would therefore be of value even if the work carrying head had 10 no movement, and hence I propose to use them in machines having either fixed or movable heads.

Having thus described my invention, I claim and desire to secure by Letters Patent—

1. The combination in a shingle siding machine, of an incising knife and a chip cutting knife working at right angles to each other, a work carrying head, means for intermittently feeding the strip along said head, and means for causing movement of the head toward the cutting knives between successive feeding movements of the strip, so as to provide for the cutting of successive chips from the same 25 portion of the strip, substantially as specified.

2. The combination in a shingle siding machine, of means for supporting and intermittently feeding the siding strip, with the incising and chip cutting knives, the circular 30 saw, means for rotating and reciprocating the latter, and a guide bar for limiting the depth of cut of the saw, substantially as specified.

3. The combination in a shingle siding machine, of the fixed frame, the carrying head, 35 the reciprocating cutters, the operating shaft therefor, and tension rods extending from the carrying head to a point beyond the bearings for the knife operating shaft, substantially as specified.

4. The combination in a shingle siding machine, of the fixed frame, the reciprocating knives, a shaft for operating the same, the carrying head mounted upon the frame, boxes 40 connected to said carrying head by means of rods, and a shaft having cams for acting upon

said boxes so as to impart movement to the head, substantially as specified.

5. The combination in a shingle siding machine, of the main frame, cutting knives guided on said frame in directions at right 50 angles to each other, a shaft having a pair of eccentrics, a rod whereby the strap of one eccentric is connected directly to one knife slide and a pair of rods and an interposed lever whereby the other eccentric is connected to 55 the other knife slide, substantially as specified.

6. The combination in a shingle siding machine, of the fixed frame, means for supporting and intermittently feeding the siding 60 strip, a circular saw, arms carrying the spindles of said saw, a frame to which said arms are movably hung, and means for vibrating said frame, substantially as specified.

7. The combination in a shingle siding machine, of the fixed frame, means for supporting and for intermittently feeding the siding strip, a circular saw, a guide for limiting the depth of cut of said saw, arms carrying the saw spindle, a swinging frame to which said 70 arms are movably hung, and means for vibrating said frame and for imparting forward movement to the upper ends of the saw carrying arms, substantially as specified.

8. The combination of the scoring saw, arms 75 carrying the spindle of the same, a gage bar for limiting the forward movement of the saw, a vibrating frame to which the saw carrying arms are movably hung, an arm having a spring leg for pressing the saw forward, and 80 means for vibrating said arm, substantially as specified.

In testimony whereof I have signed my name to this specification in the presence of two subscribing witnesses.

LEVI H. MONTROSS.
